UNITED STATES PATENT OFFICE.

HARRY E. MIEBACH AND ARNOTT S. CAUGHEY, OF LETHBRIDGE, ALBERTA, CANADA.

TRANSMISSION BAND AND CASE COVER.

Application filed October 1, 1920. Serial No. 414,100.

To all whom it may concern:

Be it known that we, HARRY E. MIEBACH and ARNOTT S. CAUGHEY, citizens of Canada, residing at Lethbridge, Province of

Alberta, Dominion of Canada, have invented certain new and useful Improvements in Transmission Bands and Case Covers, of which the following is a specification.

10 This invention relates to an improved transmission band and casing cover for motor vehicles, and has as one of its principal objects to provide a construction whereby the transmission bands of a vehicle may, 15 without the necessity for removing the transmission cover, be readily displaced.

The invention has as a further object to provide a construction wherein the ear irons at corresponding ends of the transmission 20 bands may be detached so that the bands may simply be pulled from around the drums of the transmission.

And the invention has as a still further object to provide a construction wherein the transmission cover will be equipped with a door through which the transmission bands may be readily reached and removed.

Other and incidental objects will appear hereinafter.

30 In the drawings:

Figure 1 is a perspective view showing a transmission embodying our invention, the doors of the cover being removed.

Figure 2 is an enlarged perspective view showing one of the transmission bands with its detachable ear iron removed.

Figure 3 is an edge elevation of the band,

Figure 4 is a fragmentary section taken through the detachable ear iron of the band,

40 Figure 5 is a vertical section taken through the side door of the transmission cover, and

Figure 6 is a detail perspective view of the cover.

45 The present invention is particularly applicable to transmissions as employed on a well-known widely used type of vehicle. In Figure 1, an engine of this type of vehicle is indicated at 10. In the rear of the engine is the transmission enclosed by a cover 11. This cover as now produced is provided with a top door 12 secured by a plurality of cap screws. As is well known, the transmission includes a plurality of drums about which are arranged transmission bands, three bands in all being employed.

These bands are tightened about the drums by foot pedals 13, one pedal operating each band. From each pedal extends a pedal shaft through one side wall of the transmission cover and at their inner end portions these shafts are operatively coupled with the transmission bands. For this purpose, said bands are each, in accordance with present practice, equipped at their ends with a pair of ear irons through which the pedal shafts freely extend. These ear irons are riveted to the bands and when the bands are being removed, prevent the bands from being pulled endwise from around the drums. It accordingly becomes necessary, under present conditions, to remove the transmission cover in order to effect displacement of the bands. The present invention seeks to overcome this difficulty.

In carrying the invention into effect, we provide transmission bands 14. These bands may be formed of suitable resilient metal straps and connected to corresponding ends of the bands are ear irons 15 riveted or otherwise permanently secured in position. The ear irons 15 are similar to those as at present usually employed. Struck from the opposite end portions of the bands are upturned hooks 16 and fixed to the bands beyond said hooks are upstanding studs 17. Detachable ear irons 18 are employed. Near their outer ends these irons are formed with slots 19 to receive the hooks 16 while near their inner ends said irons are provided with openings 20 to receive the studs 17. Thus, the ear irons may first be engaged with the hooks 16 when said irons may then be positioned against the bands for projecting the studs 17 through the openings 20. Engaging through the studs 17 are cotter pins 21 locking the ear irons upon the bands and, as will be observed, said irons are provided with suitable recesses 22 to receive the cotter pins, it being possible in this manner to form the studs 17 shorter than would otherwise be necessary. The ear irons 15 and 18 are, of course, formed to coact with the shafts of the pedals 13 so that when the transmission bands are in place the pedals may be operated in the usual manner for contracting the bands.

At the side thereof opposite the pedals 13, the transmission cover 11 is formed with a door opening about one side and the bottom of which are formed outwardly directed

flanges 23. At the opposite side of said opening is a beveled wall 24 and normally closing the opening is a side door 25. As best shown in Figure 5 of the drawings, this door is formed at one side and along its lower edge with flanges 26 mating with the flanges 23 and engaging through said flanges are pairs of cap screws 27. At its opposite side, the door is formed with a beveled edge mating with the beveled wall 24 of the door opening and engaging through the adjacent margin of the door and through said wall is a pair of cap screws 28. A gasket is preferably arranged between the flanges 23 and 26 as well as between the beveled edge of the door and the wall 24 so that, as will be seen, the pair of cap screws 28 may be adjusted for shifting the door to tightly bind against the gasket, the openings in the lowermost of the door flanges as well as the openings in the door for the cap screws 28 being slightly elongated to permit of lateral shifting of the door. At its upper edge the door is formed with a flange 29 mating with the usual flange upon the transmission cover for the top door 12 so that after the door 25 has been secured in place, the door 12 may be applied. Threaded through the door 25 is the usual low speed 30 adjusting screw 30 carrying the customary lock nut 31.

As will now be readily understood in view of the preceding description, the door 12 may be displaced when, by removing the door 25, access may be readily had to the ear irons 18. Then, by removing the nuts, washers and springs upon the pedal shafts, the cotter pins 21 may be displaced and the ear irons detached. This done, the transmission bands may simply be drawn endwise from around the drums of the transmission through the side door opening of the transmission cover. We accordingly provide an arrangement whereby, as will be seen, the transmission bands may be easily and quickly removed and, of course, the bands may be as easily again applied. Further, removal and replacement of the transmission bands may be accomplished without displacing the transmission cover.

Threaded into the upper edge of the side door 25 through the top door 12, are spaced

cap screws 32 for additionally bracing the side door. In connection with removal of the band, it may be well to note that after the adjusting nut upon the end of the reverse pedal shaft has been displaced, said shaft should be withdrawn endwise through its bearing sleeve for the greater portion of the length of the shaft so as to provide clearance, making the subsequent removal of the reverse band more convenient. After this band has been removed, the low speed and brake bands may then, in turn, be slipped forward into the position normally occupied by the reverse band so that the low speed and brake bands may be removed with facility.

Having thus described the invention, what is claimed as new is:

1. A transmission band including a metallic strap having a transverse angular hook struck up therefrom adjacent one end, an ear iron having an angular opening therethrough receiving said hook, a post projecting from the strap between the hook and the end of the strap and extending through the ear iron, locking means detachably engaging the post and securing the ear iron in position, and a coacting ear iron fixedly mounted upon the opposite end portion of the strap.

2. A transmission band including a metallic strap having a transverse angular hook struck up therefrom near one end, an ear iron having an angular opening therethrough adjacent its outer end receiving said hook and having a second opening between the first opening and its inner end, a post projecting from the strap through the second opening in the ear iron in advance of the hook, the ear iron being provided in its outer side with a longitudinal recess intersecting said second opening, a key engaging through the post and seated in said recess and bearing upon the ear iron to lock the same in position, and a coacting ear iron fixedly mounted upon the opposite end portion of the strap.

In testimony whereof we affix our signatures.

HARRY E. MIEBACH. [L.S.]
ARNOTT S. CAUGHEY. [L.S.]
